US0D1067895S

(12) **United States Design Patent** (10) **Patent No.:** **US D1,067,895 S**
(45) **Date of Patent:** **** Mar. 25, 2025**

(54) **SOLAR LIGHT WITH SPEAKER**

(71) Applicant: **POWER BEAUTY(DONGGUAN) INDUSTRIAL CO., LTD.**, Dongguan (CN)

(72) Inventor: **Yiqun Xu**, Dongguan (CN)

(73) Assignee: **POWER BEAUTY(DONGGUAN) INDUSTRIAL CO., LTD.**, Dongguan (CN)

(**) Term: **15 Years**

(21) Appl. No.: **29/891,131**

(22) Filed: **May 1, 2023**

(51) **LOC (15) Cl.** **14-01**

(52) **U.S. Cl.**

USPC **D14/207**; D26/57

(58) **Field of Classification Search**

USPC D26/24, 26, 37–52, 57, 93–94, 102–112; D14/194–195, 197, 204, 207, 209.1, 210, D14/213, 215–216; D13/102

CPC H04R 1/028; F21V 33/0056

(57) **CLAIM**

The ornamental design for a solar light with speaker as shown and described.

DESCRIPTION

FIG. 1 is a perspective view of a solar light with speaker showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines in the drawings depict boundaries of the solar light with speaker of the claimed design. The highlighted areas within the broken lines depict portions of the solar light with speaker of the claimed design. The broken lines and the highlighted areas within the broken lines form no part of the claimed design.

1 Claim, 9 Drawing Sheets
